UNITED STATES PATENT OFFICE.

JAMES F. MUNSIE, OF BROOKLYN, ASSIGNOR TO THOMAS L. COLES, OF NEW YORK, N. Y.

DUCT FOR ELECTRIC CONDUCTORS.

SPECIFICATION forming part of Letters Patent No. 426,205, dated April 22, 1890.

Application filed January 17, 1890. Serial No. 337,249. (No model.)

To all whom it may concern:

Be it known that I, JAMES F. MUNSIE, a British subject, residing at Brooklyn, in the county of Kings and State of New York, have 5 invented certain new and useful Improvements in Ducts or Conduits for Electrical Conductors; and I do hereby declare the following to be a full, clear, and exact description of the invention, such as will enable others 10 skilled in the art to which it appertains to make and use the same.

My invention relates to certain new and useful improvements in ducts or conduits for electrical conductors, and particularly to 15 means for constructing such ducts or conduits of highly-incombustible materials and in any desired length without irregularities at the joints.

In the accompanying drawings, Figure 1 20 represents a central longitudinal section of a portion of a duct or conduit embodying my invention, and Fig. 2 represents a cross-section thereof, taken on the line 2 2 of Fig. 1.

Similar numerals of reference indicate similar parts in both views.

The duct or conduit is composed of two 25 concentric pipes 3 4, having an intermediate filling of pulverized mica, together with a small quantity of silicate of soda and white 30 glue or other non-inflammable agglutinating mixture or compound.

Packing-rings 5 are employed in the construction of the compound pipe for the purpose of compressing or packing down the filling-in material, and are left in place, so as 35 afterward to aid in preserving the proper separation between the two pipes and to strengthen the entire structure.

The outer pipe 3 is made preferably of 40 glass or metal having an incorrodible surface, so as to resist both decay and the attacks of insects and rodents. The inner pipe 4 and the packing-rings 5 are made of a paper-pulp rendered non-inflammable and water-proof by 45 special treatment.

The special treatment referred to is described in my application for Letters Patent, Serial No. 337,246, filed January 17, 1890. It 50 consists in washing or boiling the paper-pulp in a solution of common salt, sulphate of

aluminum, and sulphate of zinc until the entire mass of pulp is completely impregnated with the said solution. The solution, after having acted upon the pulp, is then drained off, and an equal part, by weight, of finely-pulverized fire-clay and an equal part, by weight, of finely-pulverized Portland cement, is added to it, together with a sufficient quantity of white glue and silicate of soda to agglutinate and combine the whole. An intimate homogeneous mixture of these constituent parts is secured by mechanical agitators or mixers. The mixture thus obtained may then be molded into the form of the pipe 4 and rings 5. The molded products are thereupon thoroughly dried in a suitable oven, and while still hot are immersed in a hot bath of india-rubber or of fire-proof paint, (known commercially as "mineral paint.") The hot liquid is absorbed by the heated mass of the article 60 plunged into it, and any existing pores are filled, thereby rendering the article thoroughly water-proof. In order (when rubber is employed) to render said rubber non-inflammable, the article may thereafter be subjected to the ordinary vulcanizing process.

The intervening space between the concentric pipes is closed at the ends by a sleeve, serving at the same time to unite adjoining pipe-sections. The sleeve is provided at its 65 central portion with an outer flange 6 and an inner flange 7, which are respectively flush with the outer wall of the pipe 3 and the inner wall of the pipe 4. The main body portions 8 of the sleeve extend into and close the 70 ends of the intervening space between the concentric pipes, and a light coating of cement 9 unites them to the pipe 3. About the joint thus made is passed a coupling sleeve or ring 10, held in place by screws 11, which 75 pass through it and the outer pipe 3 and bear against the inner sleeve, as shown. The coupling-sleeve is preferably made of metal; but the inner sleeve is formed of the same material as the pipe 4.

The construction of joint shown and described is of especial importance in connection with ducts or conduits of the general character to which this invention is particularly applicable. The inner sleeve serves not 80 85 90 95 100

only as a connection between the adjacent sections of the duct, but also serves to close the end of the intervening space during the manufacture of the pipe. The joint is without internal projection within the walls of the pipe 4, and therefore said pipe when laid presents a smooth unbroken inner surface from end to end particularly appropriate to the insertion of electrical conductors and as to water-proof and non-inflammable at the joints as throughout its general extent.

Having thus described my invention, what I claim, and desire to secure by Letters Patent, is—

1. A duct or conduit for electrical conductors, consisting of the concentric pipes 3 4, having an intervening filling, in combination with the sleeve 8, serving to fill the ends of the intervening spaces in adjacent duct-sections and provided with an inner flange 7 and an outer flange 6, substantially as and for the purposes described.

2. A duct or conduit for electrical conductors, consisting of the concentric pipes 3 4, having an intervening filling, in combination with a connecting-sleeve serving to fill the ends of the intervening space in adjacent

duct-sections and cemented within said ends, substantially as and for the purposes described.

3. A duct or conduit for electrical conductors, consisting of the concentric pipes 3 4, having an intervening filling, in combination with a connecting-sleeve serving to fill the ends of the intervening space in adjacent duct-sections and cemented within said ends and provided with an inner flange 7 and an outer flange 6, substantially as and for the purposes described.

4. A duct or conduit for electrical conductors, consisting of the concentric pipes 3 4, having an intervening filling, in combination with the sleeve 8, serving to fill the ends of the intervening spaces in adjacent duct-sections and provided with an inner flange 7 and an outer flange 6, and an outer sleeve 10, connected to the outer pipe by screws 11, substantially as and for the purposes described.

In testimony whereof I affix my signature in presence of two witnesses.

JAMES F. MUNSIE.
